REFRIGERATOR SHELF

Thomas J. Morton, Jr., Evansville, Ind., assignor to Hoosier Cardinal Corporation, Evansville, Ind., a corporation of Indiana

Application December 14, 1955, Serial No. 553,095

6 Claims. (Cl. 211—153)

This invention relates to a new and improved metal shelf structure and to a method for producing the same. More particularly, the invention is concerned with a refrigerator shelf comprised of parallel, spaced crossbars and a peripheral frame which provides a means for supporting said crossbars and functions as a skid for sliding the shelf in and out of a refrigerator.

It is an object of the invention to produce a refrigerator shelf which will possess an improved design and appearance, and which is adapted for construction from extruded shapes and round bars. Another object of the invention is to provide an improved arrangement for securing the ends of the bars to the peripheral frame.

In accordance with the invention there is provided a generally rectangular peripheral frame and a series of spaced bars extending across such frame and having their ends secured to opposite sides thereof. Each of the frame sides to which ends of the bars are secured has a vertical web and a horizontal flange located intermediate the height of the web and projecting inwardly of the frame. The ends of the bars overlap such flange and are secured thereto as by welding; and after such securing has been effected, that portion of the web which projects in a vertical plane beyond the bars is folded over the bar ends to conceal them. Conveniently, the rear side and two ends of the peripheral frame are formed of a single length of extruded stock having a general cruciform cross-section and bent into a U-shape, two coplanar arms of such section constituting the aforesaid web and one of the other arms constituting the aforesaid flange. In such an arrangement, the fourth arm of the section projects horizontally outwardly from the frame and, at the ends of the frame, constitutes flanges by which the shelf can be slidably supported. Either of the horizontal arms of the section may be cut away where its presence is not necessary or where it would interfere with the bending of the stock. The front of the peripheral frame is formed of a length of stock of T-shaped section, the central flange of which is the flange to which the bar-ends are secured.

The accompanying drawings illustrate the invention:

Fig. 1 is a top elevation of a refrigerator shelf embodying my invention;

Fig. 2 is a detailed sectional view on an enlarged scale taken along the line 2—2 of Fig. 1 and shows in detail the folding arrangement of the webs on the front and back sides of a shelf;

Fig. 3 is a detailed sectional view, also on an enlarged scale, taken along the line 3—3 of Fig. 1;

Fig. 4 is an enlarged fragmentary plan view of the top of a refrigerator shelf embodying the invention showing the relationship of the crossbars to the frames;

Fig. 5 is a fragmentary sectional view taken along the line 5—5 of Fig. 4;

Fig. 6 is a fragmentary detailed section taken along the line 6—6 of Fig. 4 showing a refrigerator shelf support and the shelf associated therewith; and

Fig. 7 is a cross-sectional view of a preferred cruciform

shape for use in forming the back and ends of the peripheral frame.

As shown in Fig. 1 crossbars 10 are disposed at spaced intervals between a frame member 12, forming the front of the shelf, and a frame member 14 forming the back. The laterally extending rod 17 is disposed between shelf ends 16 and forms a central support for the crossbars.

The front side of the shelf is made from an extruded T-shaped section having a downwardly extending flange 18, an upwardly extending flange 20, and a horizontal flange member 22 extending inwardly toward the center of the shelf, said horizontal flange preferably having a continuous welding bead 23 extending longitudinally intermediate the width of its upper face.

As can be seen in Fig. 3 the crossbars are secured to the frame as by welding said crossbars at spaced intervals to the upper face of flange 22. After all of the crossbars are affixed in position the upper flange 20 is folded down over the ends of said crossbars to provide additional rigidity to the welded joints, conceal any variations in the lengths of the cross-bars, and hold the crossbar ends down in event any of the welds break.

The back and ends of the peripheral frame are conveniently formed of a single length of extruded stock having fore-armed the cruciform cross-section shown in Fig. 7, such member being bent into a U-shape to provide the back 14 and ends 16 of the frame. Before bending, one of the horizontal arms or flanges, indicated at 24, may be removed except over the extent of the ends 16 and the stock so bent that the remaining portions of such flange will project outwardly from the frame-ends. As shown in Fig. 3, the cross-bars 10 are connected to the back of the frame, as by welding said bars at spaced intervals to the lower face of horizontal flange or arm 26 on the inside of the frame, and then folding the downwardly extending arm 28 up over the ends of the crossbars to provide a lower support for said bars and to cover up any variation in their lengths. The fourth arm 27 of the U-shaped member is left extending upwardly beyond the upper surfaces of the bars 10 to form a protective rim around three sides of the shelf.

Along the ends of the shelf the laterally extending flanges 24 project outwardly to form a skid, so that the shelf may be slid in or out of the refrigerator on a shelf-supporting lip 30 (Fig. 6) attached to the refrigerator wall. To further such function of the flange 24 it may be formed along its outer edge with a downwardly extending lip 31.

Centrally along each end of the shelf the laterally extending flange 26 is sheared from the vertical web 27-28 and offset downwardly to a level coplanar with the bottom of the crossbars 10 as shown at 33 so that the lower face of said section may engage the upper edge of the laterally extending bar 17, which may then be welded to the offset sections 33 to provide a support for the intermediate portions of the crossbars 10.

At the front of the shelf, the flange 26 projects forwardly beyond the ends of the web 27-28 and is again offset downwardly, as at 35 (Fig. 2), to bring its lower face coplanar with the bottoms of the crossbars 10, so that it may lie on top of flange 22 and be welded thereto with the bars 10, thereby securing the two frame members together to form a continuous peripheral frame for the shelf.

I claim as my invention:

1. A shelf structure, comprising a first member in the form of a length of metal stock bent into a general U-shape to form one side and two ends of a generally rectangular peripheral frame, a second member forming the fourth side of said frame, each of said members having a vertical web and a horizontal flange projecting inwardly of the frame, and a series of crossbars extend-

ing between the second member and the side-forming portion of said first member, the ends of said crossbars overlapping and being secured to said flanges, the flange on said first member projecting beyond the web thereof at the ends of the first member into overlapping relation with the flange of the second member and being secured thereto to hold said two members rigidly together.

2. A shelf structure as set forth in claim 1 with the addition that said crossbars lie beneath the plane of the horizontal flange of said first member, opposite portions of said flange intermediate the extent of the frame-ends being offset downwardly to bring their lower surfaces into substantially coplanar relationship with the bottoms of said crossbars, and a bar-supporting rod extending longitudinally of the shelf beneath the crossbars and said offset flange portions and secured to the latter.

3. A shelf structure as set forth in claim 1 with the addition that at least over a substantial extent of the frame-ends said U-shaped stock is of cruciform cross-section having two substantially coplanar arms constituting said vertical web, a third arm constituting said flange, and a fourth arm projecting horizontally outwardly on two ends of the shelf for engagement with a shelf support.

4. A shelf structure as set forth in claim 1 with the addition that the horizontal flanges of said two members lie intermediate the vertical extents of the respective webs, the flange of the second member lying below the ends of the crossbars to which it is secured, and the upper portion of the web of the second member being folded inwardly of the frame to overlie such crossbar-ends.

5. In a shelf structure, a generally rectangular peripheral frame comprising first and second members, said first member comprising a length of metal stock bent into a general U-shape the intermediate stretch of which serves as one side of said frame, said second member extending between the ends of the other stretches of said first member and constituting the other side of said frame, each of said members being formed of stock having a vertically extending web and a horizontal flange located intermediate the height of said web and projecting inwardly of the frame, and a series of crossbars extending across said frame with their ends lying beneath the horizontal flange of the first member and above the horizontal flange of the second member, the lower marginal portion of the web of said first member being bent upwardly

and inwardly of the frame to cooperate with the adjacent flange in maintaining the adjacent ends of the crossbars in coplanar relationship, and the upper marginal portion of the flange of said second member being bent downwardly and inwardly of the frame over the adjacent ends of the crossbars into opposed relation to the associated flange to cooperate with such flange in maintaining such adjacent crossbar ends in coplanar relationship.

6. In a shelf structure, a generally rectangular peripheral frame comprising first and second members, said first member comprising a length of metal stock bent into a general U-shape the intermediate stretch of which serves as one side of said frame, said second member extending between the ends of the other stretches of said first member and constituting the other side of said frame, each of said members being formed of stock having a vertically extending web and a horizontal flange located intermediate the height of said web and projecting inwardly of the frame, and a series of crossbars extending across said frame with their ends overlapping the flanges of said first and second members and secured thereto, a marginal portion of the web of at least one of said two members being bent over the adjacent ends of said crossbars into opposed spaced relation to the associated flange to cooperate with such flange in maintaining the ends of the crossbars in coplanar relationship, the stock of which said first member is formed having a second horizontal flange extending along and projecting outwardly from the ends of the frame for engagement with a shelf-support.
